Primary Examiner — David G Muller*Assistant Examiner* — Christina Gabrielle Cosden(74) *Attorney, Agent, or Firm* — Husch Blackwell LLP(57) **CLAIM**

I claim the ornamental design for a latch, as shown and described.

DESCRIPTION

FIG. 1 is a perspective view of a latch;

FIG. 2 is a top plan view of the latch;

FIG. 3 is a front elevation view of the latch;

FIG. 4 is a right side elevation view of the latch;

FIG. 5 is a rear elevation view of the latch;

FIG. 6 is a left side elevation view of the latch;

FIG. 7 is a bottom plan view of the latch; and,

FIG. 8 is a perspective view of the latch in a closed configuration.

Broken lines shown in the drawing views are included for illustrative purposes only and form no part of the claimed design.
